TIRE

Robert L. French, Cuyahoga Falls, Ohio, assignor to The Goodyear Tire & Rubber Company, Akron, Ohio, a corporation of Ohio

Filed Jan 31, 1962, Ser. No. 68,597

Term of patent 14 years

(Cl. D90—20)

FIG. 3

FIG. 1 is a perspective view of a tire, showing my new design;

FIG. 2 is a cross-sectional view taken on the line 2—2 of FIG. 1; and

FIG. 3 is a plan view of a portion thereof.

It is understood that the portions shown in full lines are continuous around the circumference of the tire.

I claim:

The ornamental design for a tire, as shown and described.
